UNITED STATES PATENT OFFICE

2,563,276

GOLF SWING PRACTICING DEVICE

Arthur Riley, Sudbury, Ontario, Canada

Application May 1, 1950, Serial No. 159,357

4 Claims. (Cl. 273—35)

1

This invention relates to a device for practicing golf swings.

The principal object of the invention is to provide golfers with a device somewhat resembling a golf club with which golf swings may be practised with respect to a fixed upright peg rather than a conventional golf ball, so that the practising may be carried out in a confined area. When a desirably accurate swing is made with the device of my invention the fixed peg passes through two vertical channels formed in the base portion of the device.

It is a further object of the invention to provide a golf swing practicing device which is adjustable so that, as well as practising straight swings, the golfer may practise "pulls" and "slices."

It is a further object of the invention to provide a golf practicing device which leads the user to hit his golf balls with the middle of the club face.

With these and other objects in view, the device of my invention comprises a shaft resembling the shaft of a conventional golf club, a head generally resembling the head of a conventional golf club but differing therefrom in that it consists of two parts held in spaced apart relationship to form a substantially vertical channel therebetween, the channel being disposed at right angles to the face of the head, a generally U-shaped frame extending rearwardly and upwardly from the top of the head and holding the two parts of the latter in their spaced apart relationship, the base portion of the U of the frame being remote from the head, and a pair of spaced vertical members mounted upon the said base portion and extending downwardly therefrom to form a second vertical channel.

I preferably space the vertical members apart a distance equal to the width of the channel in the head, and I also prefer to mount the vertical members so as to be laterally adjustable with respect to the U-shaped frame, so that the user may practise straight, pulled, and sliced swings.

Drawings are appended which show one embodiment of a device according to the invention.

In the drawings:

Figure 1 is a perspective view with the upper portion of the shaft broken away.

Figure 2 is a cross-sectional view taken along the line 2—2 in Figure 1, and

Figure 3 is a rear elevational view of a portion of the device, particularly illustrating the adjustable mounting of the vertical members.

Reference numeral 10 generally indicates the shaft of the device, and numeral 11 the head.

2

Head 11 generally resembles the head of a conventional golf club but differs therefrom in that it consists of two parts 12 and 13 held in spaced apart relationship to form a vertical channel 14 therebetween. Channel 14 is disposed at right angles to the face of the head.

A generally U-shaped frame 15 extends rearwardly and upwardly from the top of head 11 and holds parts 12 and 13 in their spaced apart relationship. The base portion 16 of the U of frame 15 is the frame portion most remote from the head 11.

Spaced apart vertical members 17 and 18 are mounted upon base portion 16 of frame 15, and extend downwardly from base portion 16 to form a vertical channel 19, which is preferably of the same width as vertical channel 14.

Longitudinal slots 20 and 21 of equal length are provided in base portion 16. Vertical members 17 and 18 are mounted upon base portion 16 by means of wing bolts 22 and 23 respectively, which pass through slots 20 and 21 respectively, and are received in threaded holes in vertical members 17 and 18 respectively. This mounting arrangement permits lateral adjustment of members 17 and 18 with respect to frame 15.

Having described the structure of an embodiment of the invention, I will now briefly describe how the device may be put to use.

An upright peg is fixed to a rubber mat, or a peg is driven vertically into the ground, the upper portion of the peg being left projecting above ground. The golfer then addresses the peg, and attempts to so swing the device that the peg passes through the vertical channels 14 and 19 during the course of the swing. (The peg is of course of smaller diameter than the width of either of the channels.)

I suggest that golfers using the device commence practicing their swings using pegs considerably narrower than the channels, and then employ pegs of increasing diameter as their skill increases.

The practise swings which would impart straight flight to a golf ball, vertical members 17 and 18 should be so adjusted that channel 19 lies directly behind channel 14. To practise swings which would impart either a "sliced" or a "pulled" flight to a ball, the members 17 and 18 should be laterally adjusted to offset channel 19 outwardly or inwardly respectively with respect to channel 14, i. e. away from or towards shaft 10.

The weight of the device advantageously closely corresponds to the weight of the conventional club which it simulates.

While the device shown in the drawing simulates a driver, it will be appreciated that other conventional club types may be simulated equally effectively.

The device of my invention has proved itself to be useful not only in practicing straight, pulled and sliced swings, but in developing for each user his correct natural stance and encouraging him to consistently strike the ball with middle portion of the club face, thus lengthening his drives.

A modification which may advantageously be applied to the device would be the provision of an outwardly extending foot portion connected to the bases of each of the vertical members 17 and 18. These outwardly extending foot portions would have rounded edges and would prevent the digging of the vertical members into the ground during poorly executed swings.

I claim:

1. A golf swing practicing device comprising a shaft resembling the shaft of a conventional golf club, a head generally resembling the head of a conventional golf club but differing therefrom in that it consists of two parts held in spaced apart relationship to form a substantially vertical channel therebetween, the channel being disposed at right angles to the face of the head, a generally U-shaped frame extending rearwardly and upwardly from the top of said head and holding 30

the two parts thereof in their spaced apart relationship, the base portion of the U of said frame being remote from said head, and a pair of spaced apart vertical members mounted upon said base portion and extending downwardly therefrom to form a second vertical channel.

5 2. A golf swing practicing device as defined in claim 1, in which said second vertical channel is of the same width as the channel in said head.

10 3. A golf swing practicing device as defined in claim 1, in which said vertical members are laterally adjustably mounted upon said frame.

15 4. A golf swing practicing device as defined in claim 2, in which said vertical members are laterally adjustably mounted upon said frame.

ARTHUR RILEY.
